UNITED STATES PATENT OFFICE.

JAMES A. JACKSON, OF IOLA, KANSAS.

ECCENTRIC.

No. 867,186.

Specification of Letters Patent.

Patented Sept. 24, 1907.

Application filed July 9, 1906. Serial No. 325,412.

To all whom it may concern:

Be it known that I, JAMES A. JACKSON, a citizen of the United States, residing at Iola, in the county of Allen and State of Kansas, have invented certain new 5 and useful Improvements in Eccentrics, of which the following is a specification.

This invention relates to shifting or changeable stroke eccentrics adapted for use on plunger jigs for cleaning and concentrating walls, for shaking screens and the 10 like; and one object of the invention is to provide a compact and efficient device whereby the throw of the eccentric may be changed while the machine is in operation, at the will of the operator; other objects of the invention are to simplify and improve the construction 15 and operation of this class of devices.

With these and other ends in view which will readily appear as the nature of the invention is better understood, the same consists in the improved construction and novel arrangement and assemblage of parts which 20 will be hereinafter fully described and particularly pointed out in the claims.

In the accompanying drawings has been illustrated a simple and preferred form of the invention; it being, however understood that no limitation is necessarily 25 made to the precise structural details therein exhibited, but that changes, alterations and modifications within the scope of the invention may be resorted to when desired.

In the drawings, Figure 1 is a top plan view showing 30 the parts comprising the invention arranged in position for operation. Fig. 2 is a vertical sectional view taken on the plane indicated by the line 2-2 in Fig. 1. Fig. 3 is an end view, the shaft carrying the eccentric being shown in section. Fig. 4 is a sectional view of the 35 sleeve or core carrying the eccentric and the adjusting means for the latter taken longitudinally of the axis of said sleeve or core, on the line 4-4 in Fig. 2. Fig. 5 is a transverse sectional view taken on the plane indicated by the line 5-5 in Fig. 4. Fig. 6 is a detail 40 plan view showing the sleeve or core mounted upon the driving shaft, the eccentric and the adjusting wedges having been removed. Fig. 7 is a transverse sectional view taken on the plane indicated by the line 7-7 in Fig. 6. Fig. 8 is a detail end view, partly in section, 45 showing the adjusting ring and the adjusting keys or wedges, detached. Fig. 9 is a detail plan view, partly in section, of the parts shown in Fig. 8. Fig. 10 is a transverse sectional view of the eccentric disk, detached.

50 Corresponding parts in the several figures are denoted by like characters of reference.

Suitably mounted upon a shaft 1 is a sleeve or core A which, in the preferred form illustrated in the drawings, is composed of two parts or members 2 and 2' having spaced flanges 3 and 3' separably connected by means of bolts 4; the flange 3' of the member 2' being

provided with a spacing block 5 engaging a recess 6 in the face of the opposing flange 3. The sleeve or core A is provided on diametrically opposite sides with longitudinal grooves 7 extending also through the sides of 60 the spacing block, and the flanges 3 and 3' are provided with slots 8 registering with said grooves. The latter afford seats for the longitudinally slidably oppositely disposed wedges or keys 9-9 which operate through the slots 8 in the flanges of the sleeves, said keys or 65 wedges being provided with stems or shanks 10 having laterally extending pins 11 that engage diametrically opposite apertures in a ring 12 which is slidably disposed upon the sleeve.

The eccentric consists of a disk 15 having a diametrical slot 16 which is suitably shaped for engagement with the spacing block 5 and the wedges 9; said slot being provided with oblique end walls 17 as clearly shown in Fig. 10 of the drawings, for engagement with the oppositely disposed wedges; said eccentric disk 75 being positioned between the flanges 3 and 3' of the sleeve members 2 and 2', and provided with slots 18 for the passage of the connecting bolts 4; the eccentric is encircled by the usual band 19 from which a rod or pitman 20 extends to the part that is to be driven 80 by said eccentric.

Suitable supports are to be provided affording bearings for the shaft 1 and the sleeve A; one such support being shown at 21, the boxing 22 of which forms a bearing in which the sleeve or core A is suitably supported 85 for rotation, said sleeve being loose upon the shaft for rotation as will be readily understood. The boxing 22 is provided with laterally extending guide pins 23 extending through suitable apertures 24 in a collar 25 which is clamped upon and securely connected with 90 the adjusting ring 12 which slides longitudinally upon the sleeve or core as herein before described and is connected with the adjusting keys or wedges. Pivotally mounted upon the support 21 is a yoke composed of a pair of arms 26 disposed adjacent to opposite sides of the 95 sleeve or core A upon the shaft 1; said yoke which as a whole is designated B, being provided at its free end with handles 27 and 27' each carrying a suitably operable engaging member such as a gravity pawl adapted for engagement with one of the series of apertures 29 in 100 a quadrant bar or plate 30 connected with the boxing 22. It will be seen that there are two separate series of apertures at different distances from the fulcrum of the yoke B and adapted to be engaged alternately by the engaging members 28. The opposite side members 26 105 of the yoke B are connected with the collar 25 by means of links 31 so that by manipulating the yoke B the collar 25 and the ring 12 may be moved longitudinally upon the sleeve or core A, thus effecting longitudinal adjustment of the keys or wedges 9 whereby the eccentric disk will be moved diametrically between the flanges 3 and 3'; the part being retained in adjusted

position by one of the engaging members 28 entering one of the apertures 29 in the quadrant plate 30. By having the two separate engaging members and the two sets of apertures in the quadrant, a very delicate 5 adjustment may be effected without danger of the wedges or adjusting keys being moved too far since, when one of the members 28 is disengaged from the quadrant and the yoke B is moved in either direction, the other engaging member will automatically enter 10 into engagement with the next aperture adjacent thereto.

From the foregoing description taken in connection with the drawings hereto annexed, the operation and advantages of this invention will be readily understood. The construction is simple and inexpensive, and of such a nature that the eccentric may be readily 15 adjusted at any time while the mechanism of which it forms a part is in motion for the purpose of regulating the throw of the eccentric rod and the parts operated 20 thereby.

Having thus fully described the invention, what I claim as new is:—

1. In a device of the class described, a sleeve or core comprising two longitudinally grooved and flanged members, one of said members being provided with a spacing 25 block engaging a recess in the opposite flanged member, connecting bolts extending through the flanges of said members, a diametrically slotted disk interposed between the flanges of the core members in slidable engagement 30 with the spacing block and having slots engaging the con-

necting bolts, and wedge shaped adjusting keys seated for longitudinal movement in the grooves of the core members, extending through slots in the flanges of the latter and engaging the ends of the diametrical slot in the disk.

2. In a device of the class described, a sleeve or core 35 having spaced flanges and diametrically opposite longitudinal grooves, wedge shaped keys slidably mounted in the longitudinal grooves and operating through slots in the flanges, a diametrically slotted disk slidably disposed between said flanges in engagement with the wedge shaped keys, there 40 being stems or shanks extending from the keys and having lugs, a sliding ring mounted upon the sleeve or core and having apertures engaging said lugs, a collar clamped upon the sliding ring and having longitudinal apertures, a fixed support or bearing, guide members extending from the 45 latter through the apertures of the clamping collar, an adjusting yoke, and links connecting the latter with the clamping collar.

3. In a device of the class described, a sleeve or core having spaced flanges and longitudinally slidable adjusting keys or wedges operating through slots in the flanges, a diametrically slotted disk interposed between the flanges in engagement with the wedges, means, including a pivoted yoke, for effecting longitudinal adjustment of the wedges, a supporting member having a quadrant plate provided 50 with two separate sets of apertures, and separate engaging members carried by the yoke for alternate engagement with the apertures in the quadrant plate.

In testimony whereof I affix my signature in the presence of two witnesses.

JAMES A. JACKSON.
